UNITED STATES PATENT OFFICE.

WALTER C. CURRAN, OF ITHACA, NEW YORK.

SASH-HOLDER.

SPECIFICATION forming part of Letters Patent No. 230,113, dated July 20, 1880.

Application filed March 22, 1880. (Model.)

To all whom it may concern:

Be it known that I, WALTER C. CURRAN, of Ithaca, Tompkins county, and State of New York, have invented a new and useful Improvement 5 in Window-Sash Holders, which invention is fully set forth in the following specification, reference being had to the accompanying drawings.

The object of my invention is to provide 10 means of holding a window-sash at any required point, and also to prevent any rattling of the sash by means of friction.

In the drawing, Figure 1 shows a sectional 15 view of the holder in position.
a is a spring pressing against and partially inclosed within a case, b, of wood or metal. c is a plug, of wood or metal, inserted into the other end of the spring a to hold the spring centrally in its place.

20 The plug c, spring a, and case b are inserted to a proper depth in a hole bored into the edge of the window-sash, and the necessary friction is produced by the pressure of the spring a forcing the case b outwardly against 25 the window-frame. This pressure of the spring can be regulated, if desired, by a screw, as

shown, working through the sash-rail against the back side of the plug c.

In one side of the case b a small groove, d, is formed, extending about three-eighths of an 30 inch from the outer end of the case. A short bent wire is driven into the outer edge of the sash, as shown, so that the outer end of said wire shall project into said groove d in the case b, and thereby form a stop, to prevent the 35 case from springing out of the hole and being lost when the sash is removed from the window.

What I claim as my invention, and desire to 40 secure by Letters Patent, is—

The combination, with a window-sash, suitably recessed, and provided with a guide-wire and an adjusting-screw, of a sash-holder fitting within the recess, and composed of the case C, 45 grooved to receive the guide-wire, the coil-spring a, and the plug c, all arranged substantially as herein set forth.

WALTER C. CURRAN.
